UNITED STATES PATENT OFFICE.

LEOPOLD SIMON, OF NEW YORK, N. Y.

SCREEN.

1,364,457.

Specification of Letters Patent.

Patented Jan. 4, 1921.

Application filed December 17, 1915. Serial No. 67,333.

To all whom it may concern:

Be it known that I, LEOPOLD SIMON, a citizen of the United States, residing at New York city, in the county of New York 5 and State of New York, have invented certain new and useful Improvements in Screens, of which the following is a full, clear, and exact description, such as will enable others skilled in the art to which it applies 10 pertains to make and use the same.

This invention relates to canopies, awnings, shades, screens and similar apparatus, and with respect to its more specific features, to collapsible screens adapted to regulate and control the admission of light and air into buildings.

One of the objects of the invention is the provision of a practical and efficient device of the character referred to, which may be 20 readily operated.

Another object of the invention is to provide a screen having a plurality of louvers, with a simple device for setting the louvers in different positions.

25 Other objects will be in part obvious and in part pointed out hereinafter.

The invention accordingly consists in the features of construction, combinations of elements and arrangement of parts which 30 will be exemplified in the construction hereinafter set forth, and the scope of the application of which will be indicated in the following claims.

In the accompanying drawings, forming 35 part of this specification, and wherein similar reference characters refer to similar parts throughout the several views—

Figure 1 is a front elevation illustrating one embodiment of the invention;

40 Fig. 2 is a vertical section of Fig. 1;

Figs. 3 and 4 are details of the means for attaching the fabric;

Figs. 5, 6 and 7 are details of the guide-ways for the ends of the blind; and

45 Fig. 8 is a detail of the construction of the door for closing the containers for the blind.

The numerals 1, 1 indicate oppositely disposed parallel guides, in the present embodiment comprising a pair of channels, or channel bars, held an adjustable distance apart by top and bottom braces 2, 2 embodying the turnbuckles 3, 3 so as to be adjustable in length to vary the distance between the guides 1, 1. These guides may be secured in proper position in or opposite

a window frame, door opening, skylight, porch opening, etc., in any suitable manner, and with the braces 2, 2 forming a generally rectangular frame, of which the guides 1, 1 60 form two sides and the braces 2, 2 the other two sides.

The numerals 4, 4 indicate a plurality, in the present case a pair of lazy-tongs disposed opposite each other and guided in 65 their extending and contracting movements by means of the channels 1, 1 and members, as pins 5, projecting from the lazy-tongs in axial alinement with the axes of the levers 6 of the lazy-tongs, these pins serving as fulcrums of the lazy-tongs and engaging the guides 1, 1. In order to reduce friction between the lazy-tongs and the guides 1, balls 7, are provided, these balls being loosely supported by the pins 5, by means of rings 8 75 carried by said pins, or some of them, and being rotatable in said rings, within said channel bars, which latter are preferably hollow bars partially circular in cross section having slots 9, through which the pins 80 5 extend. Between the levers 6 and the guides 1 washers 10 are interposed and lie against flanges 11 on said pins. For the purpose of fixing the distance between the opposite lazy-tongs, and permitting adjustment of this distance to avoid binding in the guides and tension certain screen members hereinafter referred to, braces 12 having turnbuckles 13 are employed. The braces 12 connect the lazy-tongs, serving as fulcrums for the top and bottom levers. Two cables 14 are connected to each of the lower rings of each tongs, and extend upward over pulleys 15, 15, the opposite ends of the cables being connected to counterweights 16 in the 90 passages 17, 17.

To oppositely disposed levers of each lazy-tongs the screen members or louvers 18 are connected. Viewing the invention in some aspects, these screen members may be 100 composed of any suitable material, as wood, metal, glass, etc., but it is preferred to make these members collapsible, and preferably of flexible fabric, as canvas or similar flexible material. The canvas screen members are 105 connected to but one series of levers of each lazy-tongs so that the several screen members are in generally parallel relation, and are movable toward and from each other longitudinally of the lazy-tongs, as well as 110 angularly relative to a predetermined plane, as will be apparent. The members 18 are

preferably of such width as to cause successive screen members to overlap when the lazy-tongs are in extended position. By manipulating the turnbuckles 13, the lazy-tongs 5 may be moved relatively toward or from each other so as to vary the tension of the screen members and obtain a taut condition thereof. The elasticity of the parts is ordinarily sufficient to permit this variable relation 10 between the lazy-tongs, although sufficient play between the lazy-tongs and the guides 1 may be provided for to permit this adjustment.

Ordinarily one end of the lazy-tongs will 15 be securely fastened at the upper part of the window or other opening to which the device may be applied. This may be effected by means of a suitable supporting device, as a pivoted hook or hooks 19 depending from 20 the window frame and receiving the brace 12. In the present embodiment these hooks depend from the upper brace 2, which supports a hood 20 fastened thereto and overlying the lazy-tongs, providing a chamber 25 of sufficient size to receive the lazy-tongs and the screens when upwardly collapsed. The upper end of the slot 9 may be closed in any suitable manner to take the thrust in the operation of collapsing the device. At 30 21 is a door having pintles 22 slideable in a guide channel 23 having a slot 21' through which the pintles 22 may pass. By lifting this door slightly the lower pintle may be passed through the slot 21' and the door 35 lowered until the upper pintle bears at the lower end of the channel 22, whereupon this pintle will serve as a hinge member permitting the door to be swung into position to close the hood, in which position it may be 40 secured by a latch 23' and serve to support the tongs and screens when shut. When the tongs are in extended position, they may be secured in this position by a second hook or hooks 24 which may be 45 made to overlie the lower brace 12, and similarly these latter hooks may be pivoted to the lower brace 2, and a hood 25, having a door 26, may be provided as for the upper part 50 of the window. If desired, the hoods 20 and 25 may be sunk in the window frame at the upper and lower parts thereof. It is obvious that by disconnecting the hooks 19 the tongs and screen members may be collapsed downwardly and received in the 55 lower hood, and that the hooks 19 and 24 provide detachable means to hold either end of the lazy-tongs against movement toward the opposite end.

While any suitable means may be employed 60 to secure the screen members to the levers of the lazy-tongs, it is found that a clasp, the elements of which are illustrated in Fig. 3, possesses special advantages in an apparatus of this nature. This clasp comprises a member having angularly disposed

walls 27 and 28, the wall 28 having a portion or portions 29 extending outwardly therefrom and thence, as by the part 30, toward the wall 27, but leaving an opening or space 31 between the edges of the parts 30 and the wall 27, through which opening the flexible screen member may extend.

The parts 28, 29 and 30 form a slot or way 32 for the reception of a stiffening member 33, composed of a piece of light but strong material, as wood, around which an end of a screen member 18 is folded, the end of the member being preferably overlapped by the folded material so as to present two thicknesses of this material, as seen at 34. These 80 folds having been made around the stiffening member or holder 33, these parts, as so related, are inserted in the slot 32, the opposite ends of the stiffening member being received within the slot. A keeper comprising walls 35 and 36 providing a slot 37 is preferably made of sheet metal and is slid into position so that one wall, as 37, lies in the slot 33 between the folded fabric and the wall 30, the parts 30 taking into the slot of 90 the keeper. In this wise the screen member 18 is held in the slot 32 and may be readily removed and replaced. It is to be understood that each end of each screen member is secured to the respective tongs lever in 95 the manner just described, and that the clasps may be separate devices fixed to the levers of the lazy-tongs, or the lazy-tongs levers may each be composed of bars shaped to provide the slot 32. The ends of one wall 100 of the keeper are prolonged and flexible, as indicated at 38, and when the keeper is in securing position, the ends 38 may be bent so as to be disposed transversely of the slot 32 opposite the ends of said slot, thus positively assuring retention of the stiffening member and the screen member therein.

Thus by the above described construction are accomplished, among others, the objects hereinbefore referred to.

As many changes could be made in the above construction and many apparently widely different embodiments of this invention could be made without departing from the scope thereof, it is intended that all 115 matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent is:

1. In an apparatus of the character de- 130

scribed, in combination, a plurality of screen members, means adapted to move said screen members toward and from each other and angularly relative to a predetermined plane comprising a lazy-tongs to the levers of which said screen members are respectively connected, means adapted to guide the lazy-tongs in its movement, said last-mentioned means comprising a channel, ball supports forming fulcrums for the levers of said lazy-tongs, washers between said levers and said channel, and balls rotatably disposed in said supports.

2. In an apparatus of the character described, in combination, a plurality of collapsible screen members, means adapted to move said screen members toward and from each other and angularly relative to a predetermined plane comprising a plurality of oppositely disposed lazy-tongs to levers of each of which said screen members are connected, and means adapted to adjust the distance between said lazy-tongs.

3. In an apparatus of the character described, in combination, a plurality of screen members, means adapted to move said screen members toward and from each other and angularly relatively to a predetermined plane comprising a plurality of oppositely disposed lazy-tongs to levers of each of which said screen members are connected, and pivoted hooks disposed adjacent either end of said lazy-tongs and to which the opposite ends of said lazy-tongs may be attached.

4. In an apparatus of the character described, in combination, a pair of oppositely disposed lazy-tongs and flexible fabric screen members connected to levers of said lazy-tongs, and adapted to move toward and from each other as the lazy-tongs are extended and contracted, guides with which said lazy-tongs are co-operatively associated during their extending and contracting movements, and means adapted to adjust the distance between said guides.

5. In an apparatus of the character described, in combination, a pair of oppositely disposed lazy-tongs and flexible fabric screen members connected to levers of said lazy-tongs, and adapted to move toward and from each other as the lazy-tongs are extended and contracted, and a generally rectangular frame in which said tongs are mounted, two opposite sides of said frame comprising channel bars in which the axial pins of the lazy-tongs are guided during the extension and contraction of said tongs, and the other two sides of said frame comprising brace members adjustable in length to vary the distance between said channel bars.

6. In an apparatus of the character described, in combination, a pair of oppositely disposed lazy-tongs and flexible fabric screen members connected to levers of said

lazy-tongs and adapted to move toward and from each other as the lazy-tongs are extended and contracted, and means adapted to adjust the distance between said lazy-tongs.

7. In an apparatus of the character described, in combination, a pair of oppositely disposed lazy-tongs and flexible fabric screen members connected to levers of said lazy-tongs and adapted to move toward and from each other as the lazy-tongs are extended and contracted, and means adapted to adjust the distance between said lazy-tongs comprising longitudinally extensible braces connecting said lazy-tongs at either end thereof.

8. In an apparatus of the character described, in combination, a pair of oppositely disposed lazy-tongs and flexible fabric screen members connected to levers of said lazy-tongs and adapted to move toward and from each other as the lazy-tongs are extended and contracted, guides with which said lazy-tongs are co-operatively associated during their extending and contracting movements, means adapted to adjust the distance between said guides, and means adapted to adjust the distance between said lazy-tongs.

9. In an apparatus of the character described, in combination, a pair of oppositely disposed lazy-tongs and flexible fabric screen members connected to levers of said lazy-tongs and adapted to move toward and from each other as the lazy-tongs are extended and contracted, a generally rectangular frame in which said tongs are mounted, two opposite sides of said frame comprising channel bars in which the axial pins of the lazy-tongs are guided during the extension and contraction of said tongs, and the other two sides of said frame comprising brace members adjustable in length to vary the distance between said channel bars, and means adapted to adjust the distance between said lazy-tongs comprising longitudinally extensible braces connecting said lazy-tongs at either end thereof.

10. In an apparatus of the character described, in combination, a pair of oppositely disposed lazy-tongs and flexible fabric screen members connected to levers of said lazy-tongs and adapted to move toward and from each other as the lazy-tongs are extended and contracted, and detachable means adapted to hold either end of said lazy-tongs against movement toward the opposite end.

11. In an apparatus of the character described, in combination, a pair of oppositely disposed lazy-tongs and flexible fabric screen members connected to levers of said lazy-tongs and adapted to move toward and from each other as the lazy-tongs are extended and contracted, a generally rectan-

gular frame in which said tongs are mounted, two opposite sides of said frame comprising channel bars in which the axial pins of the lazy-tongs are guided during the extension and contraction of said tongs, and the other two sides of said frame comprising brace members adjustable in length to vary the distance between said channel bars, means adapted to adjust the distance between 5 said lazy-tongs comprising longitudinally extensible braces connecting said lazy-tongs at either end thereof, and detachable means adapted to hold either end of said lazy-tongs against movement toward the opposite end.

12. In an apparatus of the character described, in combination, a pair of oppositely disposed lazy-tongs and flexible fabric screen members connected to levers of said 10 lazy-tongs, and adapted to move toward and from each other as the lazy-tongs are ex-

tended and contracted, and means adapted to adjust the tension of said screen members.

13. In an apparatus of the character described, in combination, a pair of oppositely disposed lazy tongs, screen members connected to levers of said lazy tongs adapted to move toward and from each other as the lazy tongs are extended and contracted, and means adapted to guide the lazy tongs in its movement comprising a channel, pins forming fulcrum points for said lazy tongs and having ball supporting rings entering said channels, and balls in said channel supported by said rings.

35
In testimony whereof I affix my signature, in the presence of two witnesses.

LEOPOLD SIMON.
